UNITED STATES PATENT OFFICE.

WILLIAM A. STEBBINS, OF SEATTLE, WASHINGTON.

RAZOR.

1,347,234.

Specification of Letters Patent.

Patented July 20, 1920.

Application filed November 4, 1918. Serial No. 261,033.

To all whom it may concern:

Be it known that I, WILLIAM A. STEBBINS, a citizen of the United States, residing at Seattle, in the county of King and State 5 of Washington, have invented certain new and useful Improvements in Razors, of which the following is a specification.

This invention relates to razors and the primary object thereof is to provide an improved construction of razor embodying a blade carrier with which the cutting blade may be removably connected, thus permitting the blade to be reversed if provided with a double cutting edge or removed entirely when it is desired to replace the same with a new blade.

Another object of the invention resides in the provision of improved means for supporting the blade upon the carrier and securing the same thereto.

Another object of the invention resides in the provision of a novel form of clamping plate for maintaining the blade in proper position against one side of the carrier, the 25 carrier being equipped with suitable means to prevent any movement of the blade therebetween and the clamping plate.

These and other objects of the invention as well as the specific details of construction 30 and combination of the various elements thereof will be more readily comprehended from the following description and accompanying drawings, in which:—

Figure 1 is a view in elevation of a razor 35 constructed in accordance with my invention, the clamping plate being moved to one side to disclose the method of fastening the blade therebetween and the carrier.

Fig. 2 is an edge view of the construction 40 shown in Fig. 1, and

Fig. 3 is a transverse sectional view taken on the line 3—3 of Fig. 1.

The handle of my improved razor is of conventional form consisting of a pair of plates 1 and 2 riveted together at one end as indicated at 3 and having the opposite ends thereof connected by a pivot pin 4. Connected with this pivot pin 4 is the reduced end 5 of a blade carrier bar 6, the 45 latter being cut away on one side as indicated at 7 from a point designated 8 to the extreme outer end thereof. A clamping plate 9 is arranged to cooperate with the reduced side 7 of the carrier bar, and has 50 its outer end pivoted to the outer end of said carrier bar through the medium of a

transverse pivot pin 10. This clamping plate conforms in general shape and dimensions to that portion of the carrier bar which it opposes and is equipped at its inner end with a set screw 11 extending therethrough as shown and engageable in a socket 12 opening into the inner face of the carrier bar adjacent the point 8. At the point 8, a diagonally extending shoulder is 55 formed upon the inner face of the carrier bar and this shoulder co-operates with the correspondingly shaped end of the clamping plate to limit swinging movement of said plate in one direction and thus serves 60 to insure the proper positioning of the set screw 11 with relation to the socket 12 when the clamping plate is swung to the position indicated in Figs. 2 and 3. Adjacent this shoulder 8, the carrier bar 6 is provided with 65 a stud 13 projecting beyond the inner or reduced face 7 thereof. This stud may be made separable from the carrier bar as shown in Fig. 3 or may be made integral therewith if desired.

The cutting blade indicated at 14 is insertible between the clamping plate 9 and the carrier bar 6 as indicated in Fig. 1. The forward end of this cutting blade is provided with a slot 15 to accommodate the 70 pivot pin 10 connecting said clamping plate and carrier bar. Adjacent the rear end thereof, the cutting blade is equipped with a transverse opening 16 to receive the stud 13 and thus it will be seen from this construction 75 that the blade will be positively held against possibility of swinging movement when secured between the clamping plate 9 and the carrier. The clamping pressure of the plate 14 may be regulated by rotation 80 of the screw when the latter is engaged in the socket 12.

From the foregoing description and accompanying drawings it will be evident 85 that when it is desired to use this improved form of razor, the clamping plate 9 is swung to the position shown in Fig. 1. The blade 14 is then arranged in position with the slot 15 thereof receiving the pivot pin 10 and the opening 16 thereof accommodating the stud 13. The plate 9 is then swung to the 90 position shown in Fig. 2 and the set screw 11 is rotated into engagement with the socket 12 to prevent accidental displacement 95 of the plate. Owing to this construction, it will be seen that if the blade is provided 100

110

with a double cutting edge the same may be readily removed from between the clamping plate and carrier bar to present the unused cutting edge for use. By cutting away the carrier bar 6 upon one side it will be seen that when the blade and clamping plate are assembled as in Fig. 2, the width of the carrier bar will not be increased to such an extent as to prevent the same being properly received between the plates 1 and 2 of the handle as is usual when the razor is folded. The handle is similar to the handle of an ordinary straight razor and the blade carrying structure is designed to be received between the plates 1 and 2 of the handle in the well known manner. The particular structure of the blade holder and carrier, therefore, is especially adapted for the straight razor handle so that the edges of the blade are protected while the device is not in use.

The foregoing description and accompanying drawings have reference to what might be considered to be the preferred or approved form of my invention. I desire it to be understood that I may make such changes in the construction, combination and arrangement of parts, materials, dimensions, et cetera, as may prove expedient and fall within the scope of the appended claims.

Having thus fully described my invention, what I claim as new and desire to secure by Letters Patent, is;

35 1. A razor including a carrier bar provided with a tang and having a portion of

its inner face removed and equipped with a blade, a bar to clamp said blade pivoted at one end to the carrier bar, said pivot performing the additional function of seating 40 the end of the blade and positioned medial of the blade to admit of a reversal of the blade edges, said means including a pin likewise medially positioned and having its opposite end formed to co-act with the latter to limit movement of the said carrier bar, and means to secure the clamping bar to the latter.

2. A razor including a carrier bar provided with a tang and having a portion of 50 its inner face removed and equipped with a blade, a bar to clamp said blade pivoted at one end to the carrier bar, said pivot performing the additional function of seating the end of the blade and positioned medial 55 of the blade to admit of a reversal of the blade edges, said means including a pin likewise medially positioned and having its opposite end formed to co-act with the latter to limit movement of the said carrier 60 bar, and means to secure the clamp to the latter, the said carrier bar having an oblique shoulder, and the said clamp plate having an oblique terminal complementing the oblique shoulder of the carrier bar. 65

In testimony whereof I affix my signature in presence of two witnesses.

WILLIAM A. STEBBINS.
